WIRE COATING APPARATUS

Ray C. Kivley, Kenmore, N. Y., assignor to Western Electric Company, Incorporated, New York, N. Y., a corporation of New York

Application June 17, 1949, Serial No. 99,792

7 Claims. (Cl. 91—51)

1

This invention relates to wire coating apparatus and more particularly to apparatus for enameling wires to be employed as insulated electrical conductors. When this type of wire is to be used for winding coils, it is of course, essential that the coating be substantially continuous and yet not excessively thick in order to obtain coils of the proper space factor. In one well-known type of wire enameling machine, pluralities of wires receive their coatings in passing through grooves in a long steel roller running in a tank of enamel and provided with a doctor blade for removing the excess of enamel from the roller. When the thickness of the coating applied must be held within very close limits, it is found that a considerable proportion of the output of such a machine is unsatisfactory. When the machine is stopped for any extended period, the enamel hardens on the heavy roller and presents a difficult cleaning problem in conditioning the roller for further use.

The principal object of this invention is to improve the uniformity in the thickness of the coating applied to the wires and a further object is to eliminate the necessity of cleaning the roller.

The roller comprises a plurality of sections, each short in length to conform accurately to the contour of the applicator, removably connected together and to a suitable drive. The applicator channel, in which the roller sections rest, has bridges for supporting the end portions of the roller sections and underpasses at the bridges for conveying the material throughout the length of the applicator.

In its operating position the applicator is supported above a tank of the coating material in which it may be submerged with the roller to prevent hardening of the material on the roller sections when the apparatus is not in use. When in use, the accurate registration of the roller sections with the applicator applies to the wires, a coating of the material which is of substantially constant and uniform thickness for all the wires.

Other objects and advantages will be apparent from the following detailed description when considered in conjunction with the accompanying drawings, wherein

Fig. 1 is a fragmentary top plan view of the wire coating apparatus;

Fig. 2 is an enlarged fragmentary sectional view taken along the line 2—2 of Fig. 1;

Fig. 3 is a fragmentary vertical sectional view through the apparatus;

Fig. 4 is an enlarged fragmentary sectional view taken along the line 4—4 of Fig. 3;

2

Fig. 5 is an enlarged fragmentary sectional view taken along the line 5—5 of Fig. 3;

Fig. 6 is an enlarged fragmentary sectional view of one end of the apparatus illustrating a portion of the driving means removed and the applicator with the roller submerged in the bath of material in the receptacle; and

Fig. 7 is an enlarged fragmentary detailed view of the connecting means between the roller sections and the structure of the bridge and underpass of the applicator.

Referring now to the drawings, the apparatus includes a tank or receptacle 10 mounted at a fixed position to receive a bath of coating material 11, an overflow 12 mounted in the receptacle maintaining the material at a given level.

An applicator 14 is of a given length and has a longitudinal channel 15 in its upper surface partially conforming to a roller indicated generally at 16 to serve as a bearing support for the roller and as a wiper to control the material 11 supplied to strands 17 guided over by the roller. The roller 16 is provided with a central plane section 18 and grooved end sections 19. In the present embodiment of the invention there are six grooved sections 19, three upon each side of the plane central section 18. The ends of the sections 18 and 19 have notches 20 therein to receive the connecting tongues or flanges 21 of couplings or connectors 22 as shown more clearly in Fig. 7. The couplings 22 are interposed between each of the sections of the roller 16 to connect them with each other and at the right end of the roller to form operative connection with a removable shaft 23.

To complete the description of the applicator 14, attention is first directed to the U-shaped brackets 25 and 26 mounted at opposite ends of the applicator and having threaded apertures 40 to receive thumb screws 27 and 28 positioned to rest upon ends 29 and 30 of the tank or receptacle 11 and to support the applicator with the roller in the operating position shown in Fig. 3 or to function in lowering the applicator with the roller within the bath of material 11 as shown in Fig. 6. A guide screw 33 carried by the bracket 26 has an inner end 34 extending into a vertical slot 35 in the end 29 to assist in guiding the applicator 14 and roller 16 when moved relative to the tank 10 and to maintain their positions relative to the tank during normal operation of the apparatus. The bracket 25, particularly the inner portion 31 thereof, is provided with a passageway 38 normally closed at the top by a plug 39 and communicating near its lower end

the entrance end of the channel 15. A supply line 40, opening into the passageway 38 and thus connected to the entrance end of the channel 15, is connected to a suitable supply (not shown) to force the material 11 at a given rate of speed and at a given volume through the channel 15. It will be noted that an underpass portion 42 of the entrance end of the channel extends beneath a bridge 43 which supports the inner or left end of the roller 16, while similar bridges 44 support the intermediate connected ends of the sections of the roller over underpasses 45 of the channel and a bridge 46 supports the right end of the roller adjacent an exit end 47 of the channel. The channel 15 has lower cuts or portions 50 connecting the underpasses and linking them with the supply line 40 and the exit end 47 whereby the material 11 may flow continuously through the channel 15 of the applicator 14 free of the ends of the roller and the couplings and connected ends of the sections thereof.

The bracket 26 is provided with aligned apertures 53 and 54 to be aligned with an aperture 55 in the end 30 when in the operating position to receive the spindle 23 as well as a bearing 56 for the spindle. The end 30 for the tank 10 has a vertical groove 58 therein to receive spaced guides 59 and 60 to cooperate with the threaded element 33, or the portion 34 thereof, disposed in the groove 35 to maintain the applicator with the roller at a given position during normal operation of the apparatus and to guide the applicator with the roller into the tank 10 and the bath of material 11 disposed in the tank when the apparatus is not in use. A pin 61 mounted on the outer end of the guide 60 forms an interconnecting association with the groove 58, particularly lateral projections 62 thereof as shown in Fig. 1.

The spindle 23 has its inner end notched at 64 for operative connection with the flange or tongue portion 21 of the adjacent coupling 22 and supports an annular flange 65 short of its inner end to eliminate the possibility of the material 11 flowing on the spindle to the bearing 56. A supporting clamp 67 mounted on the bracket 26 is apertured to receive and support the bearing 56 in alignment with the apertures 53 and 54, the clamp having split portions 68 which may be drawn tightly about the bearing 56 by a manually actuatable threaded element 70 to removably hold the bearing 56 with the spindle 23 in operating position. A gear 71 mounted on the outer end of the spindle 23 interengages a gear 72 which is mounted upon one end of a drive shaft 73, this shaft extending through bearings 74 and a tubular sleeve 75 and a pulley 76 is mounted on the other left end of the shaft for operative connection through a belt 77 with a driving means (not shown).

During normal operation of the apparatus, with the applicator in the position shown in Fig. 3, and the spindle 23 with its gear 71, is mounted in position and initially urged to the left (Fig. 3) to assure positive connection with the roller 16 and connection of the sections of the rollers with each other through their couplings, the thrust being absorbed by a thrust bearing 80 having a single ball-like bearing member 81 therein to engage the adjacent surface of the member 37 of the bracket 25. The multiplicity of wires to be coated are guided through a series of annular grooves 82 of the roller sections 19 and advanced longitudinally at a given rate of speed to ad-

vance the wires through the individual quantities of the material 11 disposed in the grooves 82 of the roller while located in the channel 15 through which the wires travel. During operation of the apparatus, the coating material 11 is circulated constantly through the channel 15, including its underpasses and intermediate lower portions 50 to travel beneath the bridges 43 and 44. It will be noted that the roller 16 including all of its sections 18 and 19, is journaled in the channel 15 which partially conforms to the roller to wipe excess material from the roller causing the application of only the material 11 which enters the grooves 82 of the roller sections 19 to be applied to the wires. Furthermore, the exit end 47 of the channel 15 is provided with a weir 85 extending to the top surface of the applicator to maintain the liquid in the channel under the roller.

20 When it is desirable to stop the apparatus for a given length of time, the operator may loosen the clamp 68 and remove the spindle 23 with its bearing 56 and gear 71, after which the applicator 14 with the roller 16 may be lowered into 25 the tank to be submerged in the bath of material 11 by actuating the thumb screws 27 and 28. Here the roller with the applicator may remain eliminating the possibility of the material solidifying on the applicator or the roller and conditioning them for use when it is desirable to again place the apparatus in operation. Before raising the applicator and roller from the bath of material 11, the plug 39 is removed to prevent siphoning of the material from the applicator. 30 It is to be understood that the above described arrangements are simply illustrative of the application of the principles of the invention. Numerous other arrangements may be readily devised by those skilled in the art which will 35 embody the principles of the invention and fall within the spirit and scope thereof.

What is claimed is:

1. A wire coating apparatus comprising a roller grooved to guide a wire in a given path, 45 an applicator having a channel therein partially conforming to the roller to serve as a supporting bearing for the roller, means to direct a coating fluid through the channel to coat the wire therewith as the wire travels longitudinally through the groove of the roller, a receptacle for a bath of the coating fluid disposed beneath the applicator and roller, and mechanisms connected to the ends of the applicator to support the applicator and the roller in their coating positions and actuatable to lower the applicator and roller in the receptacle to submerge them into the bath of coating fluid when the apparatus is idle to maintain the coating material against hardening on the roller and applicator.

2. A wire coating apparatus comprising a roller grooved to guide a wire in a given path, an applicator having a channel therein partially conforming to the roller to serve as a supporting bearing for the roller, means to direct a coating fluid through the channel to coat the wire therewith as the wire travels longitudinally through the groove of the roller, a receptacle for a bath of the coating fluid disposed beneath the applicator and roller, mechanisms actuatable to lower the applicator and roller in the receptacle to submerge them into the bath of coating fluid when the apparatus is idle to maintain the coating material against hardening on the roller and applicator, the applicator having an upwardly ex-

tending portion with a passageway therein having its lower end positioned in communication with the entrance end of the channel and its upper end disposed above the bath when the roller and applicator are submerged therein, and means normally closing the passageway and removable therefrom when the applicator and roller are submerged in the bath to maintain the coating fluid against siphoning from the channel when the applicator and roller are removed from the bath.

3. A wire coating apparatus comprising a roller grooved to guide a wire in a given path, an applicator having a channel therein partially conforming to the roller to serve as a supporting bearing for the roller, means to direct a coating fluid through the channel to coat the wire therewith as the wire travels longitudinally through the groove of the roller, a receptacle for a bath of the coating fluid disposed beneath the applicator and roller, mechanisms actuatable to lower the applicator and roller in the receptacle to submerge them into the bath of coating fluid when the apparatus is idle to maintain the coating material against hardening on the roller and applicator, and elements normally retaining the applicator with the roller at a given position relative to the receptacle and to serve as guides to direct movement of the applicator in a given path into and out of the bath.

4. A wire coating apparatus comprising a roller having a plurality of sections, means interposed between the sections of the roller to connect them in axial alignment, an applicator having a channel therein partially conforming to the roller to serve as a supporting bearing therefor and to maintain the sections of the roller in axial alignment with each other, and means to direct a coating fluid through the channel to coat the wire therewith as the wire travels longitudinally through the groove of the roller, the applicator also having bridge portions adjacent the connecting means for the ends of the roller sections with adjacent underpasses for the coating fluid to respectively support the connecting means and the ends of the roller sections and to direct the coating fluid away therefrom.

5. A wire coating apparatus comprising a roller grooved to guide a wire in a given path, an applicator having a channel therein partially conforming to the roller to serve as a supporting bearing for the roller, means to direct a coating fluid through the channel to coat the wire therewith as the wire travels longitudinally through the groove of the roller, a receptacle for a bath of the coating fluid disposed beneath the applicator and roller, mechanisms actuatable to lower the applicator and roller in the receptacle to submerge them into the bath of coating fluid when the apparatus is idle to maintain the coating material against hardening on the roller and ap-

plicator, and a driving mechanism including a spindle normally connected to one end of the roller and removable from connection with the roller to free the roller for movement with the applicator into the bath.

6. A wire coating apparatus comprising a roller grooved to guide a wire in a given path, an applicator having a channel therein partially conforming to the roller to serve as a supporting bearing for the roller, means to direct a coating fluid through the channel to coat the wire therewith as the wire travels longitudinally through the groove of the roller, a receptacle for a bath of the coating fluid disposed beneath the applicator and roller, mechanisms actuatable to lower the applicator and roller in the receptacle to submerge them into the bath of coating fluid when the apparatus is idle to maintain the coating material against hardening on the roller and applicator, a driving mechanism including a spindle normally connected to one end of the roller and removable from connection with the roller to free the roller for movement with the applicator into the bath, a bearing for the spindle fixedly assembled on the shaft, a clamp to removably receive and firmly hold the bearing with the spindle in operative engagement with the adjacent end of the roller, and a thrust bearing mounted at the opposite end of the roller to absorb the thrust of the spindle.

7. A wire coating apparatus comprising a roller having a plurality of sections disposed in general alignment with each other, certain of the sections being grooved to guide wires in given paths, an element interposed between the adjacent ends of the sections to connect the roller sections together, an applicator having a channel therein partially conforming to the roller to serve as a supporting bearing therefor and to maintain the sections of the roller and the connecting elements in general alignment with each other, and means to direct a coating fluid through the channel to coat the wires therewith as the wires travel longitudinally through the grooves of the roller, the applicator also having a bridge portion, adjacent the connecting element and the adjacent ends of the roller sections with an underpass for the coating fluid to support the connecting element and the adjacent ends of the roller sections and to direct the coating fluid away therefrom.
